UNITED STATES PATENT OFFICE

2,417,880

HIGH-FREQUENCY GENERATOR

Guy Milburn and Walter H. Schnacké,
Evansville, Ind.

Application August 5, 1944, Serial No. 548,226

6 Claims. (Cl. 171—252)

1

This invention relates to an electrical generator and has as its primary object the generation of currents of high frequencies by a comparatively small structure. It has no moving coils or windings, and the frequency or cycles per second are not dependent upon circumferentially spaced windings. Furthermore, alternating current is generated with a constant direction magnetic flux. Fundamentally, the invention involves a laterally reciprocating magnetic field as opposed to a rotary field.

A further important object of the invention is to provide an extremely simple structure, not only for initial production, but in reassembly in the event some part may become damaged.

These and other objects and advantages of the invention will become apparent to those versed in the art in the following description, with reference being made to the accompanying drawings, in which:

Fig. 1 is a view in central, vertical, longitudinal section through a generator embodying the invention;

Fig. 2, a view in transverse vertical section on the line 2—2 in Fig. 1;

Fig. 3, a diagrammatic view of elements for one magnetic flux circuit; and

Fig. 4, a similar view of elements the next succeeding circuit.

Like characters of reference indicate like parts throughout the several views in the drawings.

Within a generally cylindrical housing 10 is mounted at each end stator core ring spacers 11 and 12, herein shown as held in position by the housing ends 13 and 14, which are secured to the housing 10 by any suitable means, such as by the screws 15.

Held by these spacers 11 and 12 are core rings 16 and 17, each having a like number of equidistant spaced apart slots entering from its peripheral edge. Entered within these slots, are the reduced ends 18 of alternating groups of core laminations 19 and 20, and these ends 18 are secured firmly in place by an encircling band 21 on the ring 16 and 22 on the ring 17. The bands 21 and 22 are held within the rings 11 and 12 and the laminations remain stationary.

All of the core laminations 19 and 20 are identical in size and contour, but are reversed, end for end, in alternate groups around the rings 16 and 17. Referring to Fig. 3, the lamination 19 is cut away from its inner edge top to provide, in the present showing, a rectangular slot 23 to leave an upturned leg 24 at the right end with the end 18 outside thereof and extending there-

2

from. Then, the lamination 19 has a slot 25 cut therein toward its other end to leave a leg 26 intervening between the slots 23 and 25 of substantially the same width and height of the leg 24. The slot 25, at its left side, has a marginal edge 27 sloping diagonally upwardly and outwardly to the left edge of the lamination 19, from which the end 18 extends. Preferably, the upper end of the edge 27 terminates below the common line across the top edges of the legs 26 and 24.

Each group of laminations 19 and 20 may consist of from one to any desired number of laminations, depending upon the permissible diameter of the rings 16 and 17 and the frequency and wattage to be produced. In any event, one group of laminations will be positioned as indicated in Figs. 1 and 3, and then the next adjacent group around the rings 16 and 17 will be reversed, end for end, as represented in Fig. 4.

Now with those alternately positioned laminations, there will be available a circumferential path around through all the groups to receive therein, a secondary winding 28 in the nature of a doughnut coil, so proportioned as to fit snugly within that path to have its sides in substantial contact with the left edge of the leg 26 of the lamination group 19 and the right edge of the leg 24 of the next lamination group 20, and so on entirely around the spaced lamination groups. In the group 19, there will be no contact by the laminations on left vertical side of the winding 28, due to the receding edge 27 of each lamination.

A central path across and through the lamination groups will be afforded and an exciting winding 29 is placed therein and therearound, to have the right side edge of the leg 26 in group 19 along the left side of the winding and no contact by the group 19 laminations on the right, Figs. 1 and 3, and reversely, as to group 20, to have the then left edge of the leg 26 in contact with the right side of the winding 29, and with no contact therewith on the left—a space being left between the windings 28 and 29, Fig. 4.

Furthermore, a third path is provided across and through the lamination groups 19 and 20 toward their right ends, to receive therein and therearound, the second secondary winding 30, whereby in group 19, the left side edge of the leg 24, Figs. 1 and 3, will be in contact with the right side of the winding 30, with a space between it and the exciter winding 29, while in group 20, the then right edge of the leg 26 will contact the left side of the winding 30, Fig. 4, and the edge 27 will be receding from the winding 30.

The two housing ends 13 and 14 are provided with any suitable bearings, such as ball bearings 31, to revolvably carry a shaft 42 axially of the cylinder defined by the inner edges of the lamination legs 24 and 26 and the inner sides of the windings 28, 29, and 30 which are substantially in transverse alignment therewith. Carried by this shaft 42 in any suitable manner, are a plurality of bars 32, preferably laminated, substantially parallel and spaced apart one from another to have their outer edges at a common radial distance from the axis of the shaft 42. In the present showing, these bars 32, for ease in assembly, are made in two sections, one abutting end to end with the other, and those sections have their ends received in slots of outer discs 33, 34, and inner discs 35, 36 fixed to turn with the shaft 42. The bar sections are retained in their respective disc slots by means of bands 37, 38 and 39, 40 compressively engaging over reduced height ends of the sections. The overall diameter of the circle defined by the peripheral edges of the bars is such as to bring those edges in close proximity with and just clear the ends of the legs 24 and 26 when the shaft 42 is turned by any suitable outside source of power.

While the number of lamination groups in the stator and also the number of bars in the rotor may vary, depending upon the frequency desired in connection with the rotor speed, there is a fixed ratio, in that there will be one-half as many bars 32 as there are stator lamination groups or laminated bars. For example, the drawing shows forty-eight stator bars while the rotor has twenty-four bars, giving a half cycle between adjacent stator bars. The stator formed as above described, is a two pole stator regardless of the rotor speed and the number of stator bars. It is desirable to provide ventilation through the rotor and stator, and the drawing shows one form wherein, the housing ends 13 and 14 are provided with holes 43 and 44, and the rotor discs 33 and 34 are provided with holes 45 and 46. The stator bars or lamination groups 19 and 20 are spaced from the housing 10 for free circulation therearound and therebetween. Other than the rotor bars 32, and the laminations 19 and 20, much of the generator may be made of non-ferrous materials.

The operation of the generator is best explained in reference to Figs. 3 and 4. The winding 29 is excited or energized by direct current from any suitable outside source, as in alternating current generators. In Fig. 3, the bar 32 closes (except for the slight air gaps therebetween) an iron magnetic flux path or core between the legs 24 and 26 that extend from their under interconnecting part of the bar or lamination 19, the flux set up by the winding 29, traveling as suggested by the arrow, when the bar 32 closes that core upon rotation of the rotor, to induce a current in one direction in the winding 30. Then, when the bar 32 opens that core with bar 19 to travel on to bar 20, Fig. 4, a reverse direction current is induced in the winding 30, to give the alternating current flow through one cycle.

When the bar 32 travels on to bridge between the legs 24 and 26 in Fig. 4, the other winding 28 is included within that substantially closed core, and hence current is induced in that winding 28 of alternate flow with the rapid opening and closing of the core. Thus it is to be seen that the magnetic flux reciprocates in effect, first through a closed transformer core to one side of the exciter winding and then through one to the

other side. The windings 28, 29, and 30 have suitable leads 47, 48, 49, 50 and 51, 52 respectively carried therefrom out through the housing 10, Fig. 2.

While we have herein shown and described our invention in the one precise form, it is obvious that variations in mechanical design may be made without departing from the spirit of the invention, and we therefore do not desire to be limited to that precise form beyond the limitations of the following claims.

We claim:

1. For generating high frequency currents, a plurality of closely spaced, fixed transformer core sections arranged to have terminal leg ends define an internal cylindrical opening thereacross; a circular exciter winding fixed between said legs; a secondary circular winding spaced to one side of the exciter winding fixed in relation to said pieces; a second circular, secondary winding spaced from the other side of said exciter winding and fixed in relation to said pieces; said pieces extending across all of said windings; legs on said pieces arranged to extend therefrom inwardly, alternately to have therebetween said exciter winding and said first secondary winding; and said exciter winding and said secondary winding; an armature rotatable within said cylindrical opening; and bars spaced apart around said armature arranged to tend to close a magnetic flux path therethrough alternately about said secondary windings upon rotation of the armature.

2. In a high frequency generator, a pair of spaced apart, axially aligned doughnut windings; an exciter doughnut winding axially aligned with the first windings; a plurality of iron core members spaced circumferentially around and extending transversely across said windings; legs alternately extending from adjacent core members to encompass laterally said exciter winding and one of said first windings and the exciter winding and the other of the first windings; and means to revolvably carry spaced apart iron bars across the inner terminal ends of said core members linking together said legs of each core member; whereby a variable magnetic field of constant direction, reciprocating laterally of direction of travel of said means, is set up; said bars being half in number of said core members.

3. In a high frequency generator, a stator having a plurality of magnetic flux carrying members extending transversely thereacross and spaced apart therearound, an exciter winding extending circumferentially around and across said members; a secondary winding extending circumferentially around and across said members, and legs on said members encompassing outer sides of said windings; and an armature mounted axially of said stator and having spaced apart bars extending thereacross as peripheral portions thereof substantially parallel to the armature axis, said bars being sufficiently long to bridge said legs upon travelling therewith; a second secondary winding extending around said members; said members further having on alternate ones, legs encompassing said exciter winding and said second secondary winding.

4. An electric generator comprising an exciting current carrying winding; a pair of spaced apart generated current carrying windings, between and from which said exciting winding is spaced; magnetic flux circuit members arranged for shifting one group in relation to another group thereof to alternately route the flux in a continuous direction, first around said exciter winding and one

of said generated current windings and, second, around the exciter winding and the other of said generated current windings; and means shifting one of said groups of flux circuit members in relation to the other group.

5. An electric generator comprising an exciting current carrying winding; a pair of spaced apart generated current windings, between and from which said exciting winding is spaced; magnetic flux circuit members arranged for shifting one group in relation to another group thereof to alternately route the flux in a continuous direction, first, around said exciter winding and one of said generated current windings, and second, around the exciter winding and the other of said generated current windings; means for shifting one of said groups of flux circuit members in relation to the other group; the flux members of one group comprising substantially straight bars, and the members of the other group being divided into a series of sub-groups wherein pole pieces alternately extend from bars across the three windings to be in one sub-group on the outer side of one of the generated current windings and on the opposite side of the exciter winding, and in the other group, on the outer side only of the other generated current winding and the opposite side therefrom of the exciter winding.

6. An electric generator comprising an exciting current winding; a pair of spaced apart generated current windings, between and from which said exciting winding is spaced; magnetic flux circuit members arranged for shifting one group in relation to another group thereof to alternately route the flux in a continuous direction, first, around

said exciter winding and one of said generated current windings, and second, around the exciter winding and the other of said generated current windings; means for shifting one of said groups of flux members in relation to the other group; the flux members of said one group comprising substantially straight bars, and the members of the other group being divided into a series of bars with pole pieces alternately on the outer sides only of said generated current windings and the opposite side therefrom of said exciter winding; said straight bars being of sufficient length to extend across both of said generated current windings, whereby the pole piece on the outer side of one of said generated windings is bridged with the pole piece on the opposite side of the exciter winding, and upon shifting, the straight bar successively bridges the pole piece on the outside of the other generated current winding with the pole piece on the opposite side of the exciter winding, thereby shuttling the magnetic field with constant direction flow from side to side of the exciter winding to alternately include one of said generated windings therein.
